[57] **CLAIM**

The ornamental design for combined swimming pool wall seat and stair module, as shown and described.

DESCRIPTION

FIG. 1 is a perspective view of the combined swimming pool wall seat and stair module showing my new design;

FIG. 2 is a top plan view thereof;

FIG. 3 is a cross sectional view taken along line 3—3 of

FIG. 2;

FIG. 4 is a cross sectional view taken along line 4—4 of

FIG. 2;

FIG. 5 is a left side elevational view thereof;

FIG. 6 is a rear elevational view thereof;

FIG. 7 is a right side elevational view thereof; and,

FIG. 8 is a bottom plan view thereof.

The broken lines are for purposes of illustration only

and form no part of the claimed design.

FIG. 1

FIG. 3

FIG. 2

FIG. 4

FIG. 5

FIG. 6

FIG. 7

FIG. 8
